INVENTOR

BY *Walter P. Hammar*

ATTORNEY

UNITED STATES PATENT OFFICE.

DAVID LANDAU, OF NEW YORK, N. Y.

SPRING.

1,241,744.

Specification of Letters Patent.

Patented Oct. 2, 1917.

Application filed September 13, 1916. Serial No. 119,814.

To all whom it may concern:

Be it known that I, DAVID LANDAU, a citizen of the United States, residing in the city, county, and State of New York, have 5 invented certain new and useful Improvements in Springs, of which the following is a specification.

In my Patent No. 1,199,013, dated September 19th, 1916, I have disclosed and 10 claimed certain fundamental improvements in the construction of laminated springs, which result in greatly improving springs of that character by increasing the efficiency thereof for the weight of metal used; increasing the load which such springs can 15 carry, making the spring more durable; improving the interaction of the several leaves and the stress relationship existing between them; and producing a more satisfactory stress distribution in the individual 20 leaves. I have also discussed in said patent the importance of properly tapering the ends of spring leaves, the mode of action of tapered leaves and the theory and underlying 25 principles of scientific tapering which were not theretofore known.

A very important feature of my invention set forth in said patent consists in the use 30 of an improved system of tapering the leaves by which a greater deflection efficiency of 35 the leaves is obtained. The present application, which is in part a division of the application for my patent referred to relates primarily to a particular form of taper embodying 40 the broad invention set forth in said prior patent. Other features of the present application relate to a construction for maintaining the leaves of laminated springs in alinement, to means for improving the lubrication of the leaves and to an improved form of stress rectifying slot.

In the accompanying drawings, which form a part of this specification and which illustrate certain preferred embodiments of 45 the invention, Figure 1 is a side elevation of a semi-elliptic spring. Fig. 2 is a bottom plan view of a portion of the spring shown in Fig. 1. Fig. 3 is a fragmentary side elevation, partly in vertical section, of 50 portions of the intermediate leaves of the spring shown in Fig. 1. Fig. 4 is a plan view of a portion of one of the leaves. Fig. 5 is a side elevation of a modified form of 55 spring embodying my invention. Fig. 6 is a bottom plan view of a portion of the spring shown in Fig. 5. Fig. 7 is a dia-

grammatic bottom plan view of a tapered end portion of a spring leaf illustrating my novel form of taper. Fig. 8 is a side elevation of the leaf end shown in Fig. 7. Fig. 9 60 is a similar view showing the leaf end curved as is commonly done in practice.

Referring to the drawings in detail and particularly to Figs. 1, 2, 3, and 4, the numeral 1 designates a semi-elliptic spring having a master leaf 2, which is provided at its ends with the usual eyes 3, which receive the shackle bolts by which the spring is attached to the supported load such as a vehicle body. 4 is the long plate, 5 is the short 70 plate and 6 are a series of intermediate plates, which may be more or less in number in accordance with the strength of the spring desired and the weight of the load to be supported. As illustrated the leaves are 75 inversely graded in thickness in accordance with the principles and for the reasons set forth in my previous patent, the master leaf being the thinnest and the short plate the thickest. These figures also illustrate certain other features of construction disclosed in my said patent, such as that the ends of the leaves below the master leaf are provided with tapered portions 7, which increase in fineness from the shorter toward 80 the longer plates, the end of each taper overlapping the base of the taper of the next longer plate.

The form of the taper 7 to which the present invention is particularly directed is 90 illustrated in Figs. 1 and 2 and in greater detail in Figs. 7, 8, and 9. It will be seen that in the first place, the leaves are tapered at their end portions both in thickness and in width, the taper in thickness being in the 95 general form of a trapezoid as particularly set forth and broadly claimed in my previous patent. That is to say, referring to Fig. 8, the taper in its elemental form with the leaf developed so that it is straight has 100 the outline in the plane of its thickness of a trapezoid *a*, *b*, *c*, *d*, the taper in this plane being defined by two plane surfaces, which if continued to a line of intersection would come together at a point *e*. Looking at the 105 leaf in plan, it will be seen that the taper in width is also a trapezoid, *f*, *g*, *h*, *i*, this taper being defined by vertical plane surfaces which as illustrated would also intersect at *e*. Theoretically the taper might be carried 110 out to a sharp point at *e* but for practical reasons of manufacture and use, I deem it

preferable to omit the sharp point as it performs no useful function, might break off, would tend to abrade the surface of the plate above and also introduces difficulties in the proper heat treatment of the leaves. In using the term "trapezoid" in defining these tapers, I use it as a convenient mode of expression in defining my characteristical novel form of taper rather than as a strict 10 geometrical descriptive term and the taper might be described in other words as one having a decrease in width and thickness as it proceeds from its base in accordance with a linear function of the distance from the 15 base of the taper.

Fig. 9 shows the tapered leaf illustrated in Figs. 7 and 8 curved as is frequently done in practice, the essential characteristic of the taper as "trapezoidal" in the sense in 20 which I have defined this term being preserved in that the same linear thickness and width relationship is retained and this taper, of course, falls within the term "trapezoid" as I have employed it.

25 The form of taper above described, namely, one which is trapezoidal both in thickness and width has high flexual characteristics and a very high deflection efficiency. In fact as I have ascertained by calculation 30 and experiment, the deflection efficiency of a tapered leaf end of this form is at least fifty per cent. greater than the deflection efficiency of a similar overhanging leaf end which is not tapered. This novel form of taper is 35 also particularly advantageous when used in connection with other features of invention of my previous patent such as when it is so embodied in a spring that the ends of the tapers of the shorter leaves overlap the 40 bases of the tapers of the next longer leaves.

This taper is also very advantageously utilized in connection with my inversely graded form of spring in which the leaves decrease in thickness from the short plate to 45 the master leaf and also in which the tapers increase in fineness from the short plate to the master leaf (see Fig. 1). This form of taper, however, is not limited to use in such a spring, but is generally applicable to 50 spring construction and may be employed with other forms of springs such as that described in my application, Serial No. 116,284, filed August 22nd, 1916. I have illustrated the present invention in connection with 55 such a spring in Figs. 5 and 6, in which the leaves increase in thickness from the short plate to the master leaf, the tapers decreasing in fineness in the same direction. As explained in my said application, Serial No. 60 116,284, a spring of this character has advantages for certain classes of work as when called upon to act as a strut when carrying the rear axle of a motor-propelled vehicle.

My improved form of taper may also be 65 advantageously employed in connection with

leaves provided with stress rectifying slots as described in my previous patent and one form of which is illustrated in Figs. 3 and 4.

Referring specifically to Figs. 3 and 4, it will be seen that the intermediate leaves of the spring are provided near their ends with stress rectifying slots, which as illustrated are so shaped as to provide enlarged outer portions 10 from which extend narrower 75 parallel sided portions 11. This form of slot is desirable for its stress rectifying properties, the greatest metal deletion being toward the outer end where it is usually least necessary and the parallel sides of the 80 inwardly extending portions may be advantageously used as guides to coöperate with a projection or bead 12 formed on the adjacent shorter leaf, which acts to hold the leaves in proper alinement. At the same 85 time any necessary relative movement may take place between the leaves when the spring is deflected as the bead will slide between the parallel walls.

As described in my previous patent, the 90 slots may also be advantageously employed as a means for lubricating the leaves and the bead coöperates with this function of the slot in agitating and distributing lubricant contained therein and assisting in forcing 95 the same between the leaves.

While I have shown and described in detail certain particular examples of springs, these are to be understood merely as illustrative of preferred embodiments of the 100 principle of my invention and I do not desire to limit myself thereto but intend to cover every construction in which the principle of my invention is embodied.

Having thus described my invention, I 105 claim:

1. A leaf for a laminated spring having tapers in the plane of its thickness and in the plane of its width, both of said tapers having the outlines of a trapezoid. 110

2. A laminated leaf spring comprising a plurality of leaves having central portions of substantial length and of uniform dimensions in thickness and width, said leaves having end portions tapered in the planes of 115 their width and thickness in the outlines of a trapezoid, the ends of the tapered portions of the shorter leaves overlapping the bases of the tapers of the respective next longer leaves. 120

3. A leaf for a laminated spring having its end portion tapered both in the plane of its width and plane of its thickness, the taper in both planes having the outlines of a trapezoid, said leaf being provided adjacent to the 125 base of the taper with a stress rectifying slot.

4. A laminated leaf spring in which certain of the leaves have end portions tapered in both the planes of thickness and width, 130

the taper in both planes having the outlines of a trapezoid, the ends of certain of the leaves being also provided with stress rectifying slots within the areas covered by the 5 ends of the next shorter leaves.

5. A laminated leaf spring in which certain of the leaves are provided with stress rectifying slots within the areas covered by the end portions of the next shorter leaves, 10 said shorter leaves being provided with beads coöperating with the walls of said slots in the adjacent longer leaves to maintain the leaves in alinement.

6. A leaf for a laminated spring provided with a stress rectifying slot having an enlarged outer portion and a parallel sided 15 inwardly extending portion.

7. A laminated leaf spring having lubricant pockets in the end portions of certain of the leaves within the areas covered by the 20 ends of the next shorter leaves, said shorter leaves being provided with projections extending into said lubricant pockets for agitating the lubricant therein.

DAVID LANDAU.
